UNITED STATES PATENT OFFICE.

CHARLES L. MEYER AND ROY O. MACMONAGLE, OF OMAHA, NEBRASKA.

CONCRETE-COLUMN MOLD.

1,364,946.

Specification of Letters Patent. Patented Jan. 11, 1921.

Application filed August 4, 1919. Serial No. 315,094.

To all whom it may concern:

Be it known that we, CHARLES L. MEYER and Roy O. MACMONAGLE, both citizens of the United States, residing at Omaha, in the 5 county of Douglas and State of Nebraska, have invented certain new and useful Improvements in Concrete-Column Molds, of which the following is a specification.

This invention relates to metal molds for 10 the erection of concrete columns, and the principal object of the invention is to provide a simple and efficient column mold structure inexpensive to manufacture, easy to assemble, and characterized by a high degree of strength. More specific objects of 15 the invention are, first, to provide a sheet metal sectional mold of such a structure as to leave minimum mold marks in the surface of the concrete at the vertical joints of the 20 mold, and, second, to provide an improved system of bands or hoops for supporting the cylindrical sections of the mold or form against radially bursting strains caused by the wet concrete before the latter is set or 25 hardened.

In the accompanying drawings, we have 30 illustrated a practical embodiment of the invention which in practice has been found to satisfactorily fulfil the stated objects of the invention, and referring thereto—

Figure 1 is a vertical elevation of an assembled column mold;

Fig. 2 is an enlarged cross-section on the line 2—2 of Fig. 1;

Fig. 3 is a fragmentary elevation in the 35 region of one of the main hoops or rings;

Fig. 4 is an enlarged cross-section through 40 one of the vertical lap-joints of the cylindrical form just above one of the main hoops or rings, illustrating the form of the joint and the notching of the hoop or ring to straddle the joint;

Figs. 5 and 6 are side and edge elevations 45 of one of the intermediate auxiliary hoops or bands, illustrating the longitudinal adjustability thereof; and

Fig. 7 is a fragmentary cross-section just 50 above one of the auxiliary hoops or bands showing the latter applied to the mold cylinder.

Referring to the drawings, 5, 6 and 7 designate as entireties a plurality of cylindrical sections superposed on each other in telescoped relation and together forming the 55 body portion of the mold, and 8 designates as an entirety a flared or tapered form mount-

ed on the upper body section 7 and constituting the head or cap portion of the mold.

Each of the body sections 5, 6 and 7 is made up of a plurality of transversely curved sheet metal sections 9, with their vertical edges in overlapped relation. These sheet metal sections 9 are of varying widths, and all of the sections except the narrowest are made in widths which are even multiples 60 from center to center of the joints of the width of the narrowest section. By means of this scheme which, however, is not broadly new with us, it is possible to erect the several body sections 5, 6 and 7 of the column 65 form by a proper selection of the sheet metal sections 9 so as to secure the particular diameter of any cylindrical section required.

Fig. 4 illustrates our improved form of lap-joint, from which it will be seen that the 70 metal at one vertical edge of the section is folded outwardly twice on itself, the inner fold 10 lying substantially in contact with the wall 9 and the outer reversely bent fold 11 being spaced from the inner fold 10 by the 75 thickness of the metal, thereby forming a pocket 12 which receives the outwardly offset margin 13 of the opposite vertical edge of another section. This margin 13 is offset to the extent of twice the thickness of the 80 metal, which leaves the inner surfaces of the two sections 9 flush with each other. By reason of this construction of joint, no mold-mark is left on the surface of the column 85 beyond a slight fin caused by the small 90 groove 14 in the mold between the folded margin of one section and the off-set of the other section.

Regardless of the number of sheet metal sections 9 in any cylindrical section such as 95 5, 6, or 7, the lap-joints are always spaced from center to center a fixed minimum distance or an even multiple of such minimum distance; and this fact is utilized to advantage in the construction of the main bonding 100 rings or hoops next to be described.

Referring to Figs. 2 and 3, 15 designates 105 each of a pair of semi-circular flat ring sections that are pivotally united at one end by a pivot pin 16. These ring sections surround the cylindrical mold sections with their inner edges in contact with the latter, as shown in Fig. 2, and their free ends are bent upwardly, as shown at 17 in Fig. 3, and are apertured to receive an ordinary stove-bolt 18 and nut 19, by which means the ring 110 can be tightly drawn around the cylinder.

In the inner edge of each ring are cut out notches 20, each of these notches being of a width sufficient to straddle a lap-joint of the cylinder; and these notches 20 are spaced 5 apart from center to center a distance just equal to the width of the narrowest sheet metal section 9 measured from center to center of the lap-joints between which said narrowest section lies. It follows from this 10 construction that, regardless of the number of lap-joints in any cylinder section and regardless of their spacing, the rings can always be applied with certain notches 20 thereof straddling the lap-joints, as shown 15 in Fig. 2; thereby making it unnecessary to provide specially notched rings for any given cylinder section.

These relatively heavy rings or hoops 15 are spaced at distances varying from three 20 to six feet apart in the column form, and hold the latter to a true circle; and at intervals between these main clamps we employ one or more relatively light band clamps 21, shown in detail in Figs. 5 and 6. Each of 25 these is simply a light flexible steel band approximately one and one-half inches wide, and in order to make a fixed length of band serve for the different diameter column sections, each band is provided with an outwardly turned end lug 22 at one end apertured for the passage of a stove-bolt 23 (Fig. 7), and a series of spaced holes 24 are formed therein for some distance inwardly of the other end of the band, the holes 24 serving 30 for the attachment of an angular fastening lug 25 as by means of small stove-bolts 26, the radially projecting member of the lug 25 being apertured to receive the bolt 23, as shown in Fig. 7. By reason of this construction, if the band is longer than is required 35 for one of the smaller diameter cylinder sections, the lug 25 is attached thereto a proper distance inwardly from the end of the band, and in applying the latter the projecting portion of the band beyond the lug 25 is 40 simply lapped beneath the mold-clamping portion of the band in the manner clearly 45 shown in Fig. 7.

Any desired number of these light auxiliary clamping bands may, of course be employed, or they may be omitted altogether, so far as the other novel structural features herein above described are concerned; but the use of one or more of these light auxiliary bands in association with the main hoops or bands 15 is preferred.

We claim—

1. A cylindrical mold for a concrete column, comprising a plurality of transversely curved sheet metal sections lap-jointed at their proximate vertical margins, each section having the metal on one vertical edge thereof folded backwardly on its outer side substantially in contact with the body of the

section and then reversely folded over the 65 backward fold and spaced from the latter by substantially the thickness of the metal thereby forming a narrow pocket, and having the marginal portion of the metal on its other vertical edge laterally offset on its 70 outer side to the extent of twice the thickness of the metal and disposed in a plane parallel with the plane of the section for engagement with the pocket of an adjacent section, whereby the body portions of adjacent sec- 75 tions lie in the same curved plane.

2. A cylindrical mold for a concrete column, comprising a plurality of transversely curved sheet-metal sections having external lap joints at their proximate vertical margins, said sections being of varying widths that are integers or even multiples of the narrowest section, and a clamping ring or hoop surrounding said mold and formed on its inner edge with notches straddling said 85 lap joints.

3. A cylindrical mold for a concrete column, comprising a plurality of transversely curved sheet-metal sections having external lap joints at their proximate vertical margins, said sections being of varying widths that are integers or even multiples of the narrowest section, clamping rings or hoops surrounding said mold and each formed on its inner edge with notches straddling said 95 lap joints, and one or more light clamping bands encircling said mold between said clamping rings or hoops.

4. A cylindrical mold for a concrete column, comprising a plurality of transversely curved sheet metal sections of varying widths having external lap-joints at their proximate vertical margins, said sections being of widths from center to center of said lap-joints that are integers or even multiples 100 of the width of the narrowest section, and a clamping ring or hoop surrounding said mold and formed on its inner edge with notches that are spaced from center to center 105 a distance equal to the width of said narrowest section, said notches straddling said lap-joints.

5. An auxiliary clamping band for a cylindrical concrete column mold, comprising a flexible metal band having at one end an integral bent and apertured lug and formed with a series of holes spaced at intervals from its opposite end, a detachable apertured lug, means coöperating with said holes for securing said detachable lug to said band opposite any of said holes, and a clamping bolt passed through the apertures of said lugs; the portion of said band projecting beyond said detachable lug being adapted to underlie the mold-clamping portion of the band.
